(57) **CLAIM**

The ornamental design for a clam shell packaging, as shown and described.

DESCRIPTION

FIG. 1 is a perspective view of a clam shell packaging showing the present design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a right side elevational view thereof.

The broken line showing of a die cut for hanging, magazine clip and rounded canister is included for the purpose of illustrating structural environment and forms no part of the claimed design.
